UNITED STATES PATENT OFFICE.

JOHN P. BURKHARD AND FRANK NOVOTNY, OF ST. PAUL, MINNESOTA.

BREECH-LOADING GUN.

SPECIFICATION forming part of Letters Patent No. 288,618, dated November 20, 1883.
Application filed December 22, 1882. (No model.)

To all whom it may concern:

Be it known that we, JOHN P. BURKHARD and FRANK NOVOTNY, of St. Paul, in the county of Ramsey and State of Minnesota, have invented certain new and useful Improvements in Breech-Loading Guns; and we hereby declare the following to be a full, clear, and exact description of the invention, such as will enable others skilled in the art to which it pertains to make and use the same.

Our invention relates to an improvement in breech-loading guns, the object of the same being, first, to provide improved means for automatically cocking the hammers when the barrels are tilted up at the breech to receive the cartridge. A further object is to provide means for automatically cocking the hammers and locking them in a cocked position by simply tilting the barrels up at the breech to receive the cartridges. A further object is to provide simple means for unlocking the hammers when it is desired to discharge the piece. Further, to provide simple and compact locks composed of few parts, all of which are secured to the side plates of the gun and adapted to be removed therewith. Further, to provide a safety mechanism for preventing the premature explosion of the gun in case the sear should break or become accidentally disengaged from the hammer. Further, to provide automatic indicators, so situated as to enable the gunner to perceive instantly whether the right or left or both hammers are cocked. A further object is to provide means for removably securing the barrels to the stock, and with these ends in view our invention consists in the parts and combinations of parts, as will be more fully described, and pointed out in the claims.

In the accompanying drawings, Figure 1 is a side view of a gun embodying our improvements. Fig. 2 is a plan view of the same. Fig. 3 is a longitudinal vertical sectional view. Fig. 4 shows detached views of the locking-bolts. Fig. 5 is a longitudinal sectional view of the compensating-link. Fig. 6 is a perspective view of the lower side of the active body. Fig. 7 is a similar view of the locking-bolts and top lever. Fig. 8 is a similar view of the reciprocating rod. Fig. 9 is a transverse vertical sectional view of the vertically-movable locking-bar. Fig. 10 is a side view

of the active body with one side plate in position and one removed. Fig. 11 is a view of one of the side plates with the operative parts thereon. Fig. 12 is a perspective view of one of the indicator-pins. Fig. 13 shows the locking-bar. Fig. 14 is a perspective view of the combined sear and mainspring. Fig. 15 is a vertical longitudinal sectional view of the fore part of the stock and a portion of the barrels, and Fig. 16 is a perspective view of the side plate, showing the combined sear and mainspring and the mechanism for holding the said combined spring in a depressed position.

A represents the stock; B, the active body; 65 and C, the barrels, the latter being pivotally secured to the active body in a manner to be hereinafter described.

The stock A is provided at its forward end with recesses and slots for the active body of 70 the gun and for the side and the trigger plates, the main portion of the said end, however, being undisturbed or left solid, so as to afford a firm and solid bearing for the parts attached thereto.

Each side plate, D, is of the ordinary shape, and is provided on its inner face with a concealed hammer, a, the mainspring b, the sear c, and the safety mechanism, which will be hereinafter referred to. The hammer a is provided with one or more sear notches, with which the end of the sear engages, and when in a depressed position rests up against the inward projection, e, formed integral with the side plate, D.

The V-shaped spring b is secured to the side plate in any desired manner, and acts directly on the hammer and sear, thereby dispensing with the services of an extra spring for each lock.

The sear c is provided at its rear end with an inwardly-projecting finger, d, the outer end of which latter rests over one of the triggers g, secured to the trigger-plate.

f is a finger formed integral with the hammer, and adapted to register with the notch h in the indicator F.

The indicators (one behind each barrel, and operated independently by the hammers) are pins, which pass vertically through the portion of the active body which forms the breech-block. The finger f of the hammer registers

with the slot *h* in the indicator, and moves the said indicator simultaneously with the hammer. When the hammer is moved backward to a cocked position, the indicator is also moved upward until the upper end thereof rests above the breech-block, and when the hammer falls the indicator also falls with it. By this means the gunner is able to tell at a glance if either or both hammers are cocked. These indicators, besides performing the function above described, also serve to hold the firing-pins in place, and prevent their accidental displacement.

The firing-pins *G* pass horizontally through the breech-block—one behind each barrel—and each is provided about midway its length with a cut-away portion for the passage of the indicators *F*. These firing-pins *G* are free to move a slight distance, and the rear ends thereof project through the breech-block and terminate in front of the hammer. Each hammer *a* is also provided with a curved lateral projection, *i*, with which the rear ends of the cocking-bars *H* engage. These cocking-bars 25 are L-shaped, and pass longitudinally through the active body from the point where the barrels are pivoted thereto to the hammers *a* on the face-plate. The rear portions of these cocking-bars are each provided on its upper face with a curved cut-away portion, in which the curved lateral projections *i* of the hammers *a* rest. The front end of each of these cocking-bars is provided with an inwardly-projecting arm, *j*, the ends of which latter meet in 35 the vertical center of the active body.

From the foregoing it will be seen that by exerting a pulling-force on the cocking-bars the hammers are thrown backward to a full cock, and held in such position by the sears *c*. 40 The cocking-bars are moved longitudinally by tilting the barrel, and, after the hammers are cocked, the cocking-bars can be moved without interfering with the hammers. The precise manner of operating the cocking-bars will be described farther on.

To prevent a premature explosion in case the sear should be accidentally disengaged from the hammer, we have provided an independent safety attachment adapted to engage 45 the spring *b* and hold it in a depressed position. This safety attachment is also secured to the side faces of the lock, and consists of a 'dog, *k*, and the operating-lever *k'*, both of which are set into the inner face of the side plates, so as not to interfere with the free movement of the other parts. The movement of the operating-lever *k'* is controlled by the spring *k'*, which can be formed integral with or separate from the said lever, as desired. 55 The rear end of the operating-lever *k'* terminates in an inwardly-projecting finger, *l*, which latter rests in close proximity to the finger *l* on the sear *c*. The opposite end of the lever *k'* rests in an open slot in one end of the dog *k*, while the free end of the said dog is adapted to rest over a lateral projection, *m* on the

spring *b*. The pendent arm of the dog *k* rests in front of the projection or abutment *m* on the spring *b*, and as the said spring *b* is depressed during the cocking operation, the said dog is moved to enable the projection *m* to pass downward. As soon as it passes the lower end of the pendent arm of the dog *k* (the dog) swings around by the action of the spring *k'* and bars the upward movement of the spring *b*. Thus it will be seen that if the end of the sear should by any accident whatever become disengaged from the hammer the spring would still be under control and be inoperative until released from the dog; but when it is desired to discharge the piece the trigger acts alike on the lever *k'* and the sear, and simultaneously removes all obstacles tending to hold the hammer back. These side plates, with the parts before described, are secured on opposite sides 85 of the gun by the single screw *n*, which passes through both side plates and the intervening stock.

When it is desired to clean the lock, it is simply necessary to remove the screw *n* with 90 an ordinary screw-driver and take off the plates, with the operative parts of the lock attached thereto, without disarranging any other parts, it making no difference whether the hammers are cocked or not. When this is 95 done, the entire operative parts of the lock can be easily and quickly detached from the plates for cleaning by use of the single screw-driver at hand, and as readily put together again. Again, the particular construction of 100 lock herein described permits the hammer to be snapped without in anywise endangering the gun. The front end of the active body of the gun is curved in the arc of a circle, and forms the bearing on which the barrels turn. 105 The active body is also provided with two or more openings, into which the lugs *p p'* on the under side of the barrels rest, and in which they are secured by the wedge-shaped holding-bolts *J* and *J'*. The barrels are pivoted 110 horizontally to the active body of the gun, and consequently swing in a vertical plane in opening and closing, the hooked lugs on the under side of the barrels being adapted to register with the openings in the active body. 115 The openings or slots in the lugs on the under side of the barrels are made wedge-shaped, and the breech-bolt *J* and the lower bolts, *J* and *J'*, which enter said notches, are also wedge-shaped, for a purpose to be hereinafter described. 120

The bolts *J* and *J'*, which enter the hooked lugs *p p'*, are made in separate pieces of the form shown, and move and rest in recesses formed in the active body of the gun. The rear end 125 of the lower bolts, *J J'*, is provided with an upwardly-extending arm, *q*, the upper end of which latter rests in an open slot, *r*, formed in the downward excusion *s* of the upper bolt, *J*. The rear end of the upper bolt, *J*, 130 is connected by the compensating-link *t* to the tumbler *K*, which latter in turn is connected

- to the top lever, L. The movement of this tumbler K is controlled by the spring M, the constant tendency of which is to force the bolts J J' J² outward into the notches formed 5 in the lugs p p' p² of the gun-barrels. When the lever L is turned in the proper direction, the bolts J, J', and J² are withdrawn from the notches in the catches p p' p², and the barrels are allowed to tilt.
- 10 The compensating-link t is made in two parts, one of which is provided with a female screw-threaded socket, and the other with a screw, which latter screws into the female screw-threaded socket. By simply unscrewing the parts this link can be lengthened to 15 compensate for any wear of the wedge-shaped bolts, or of the wedge-shaped notches formed in the depending lugs p p' on the under side of the gun-barrel, or the wedge-shaped notch 20 on the breech-lug p². The movement of the top lever, L, also performs another important function—viz., automatically locking the triggers against movement.
- To tilt the barrels it is necessary to move 25 the top lever, L, and when the said top lever is moved a sufficient distance to withdraw the bolts J J' J² the automatic lock or safety mechanism is also brought into operation. This safety mechanism consists of a long rod, 30 N, secured to the under side of the top plate of the active body, the front end of which rests in close proximity to the tumbler K. The central portion thereof is provided on its upper and lower faces with cams v, which later regulate the movement of the vertically- 35 movable bar w. This bar is guided by depending arms on the top plate of the active body, and is provided with an opening through which the rod N passes. The rod N is also 40 provided, back of the cams v, with notches, (preferably two,) into which the front end of the spring O rests. The rod N is also connected to the thumb-piece P, which latter slides on the upper surface of the top plate of 45 the active body. This thumb-piece P covers a mark or plate set into the active body, which can have the word "safe" engraved thereon or not, as desired, at any event denoting that when the mark or plate is covered by the piece 50 P the triggers are unlocked.
- As before stated, the front end of the rod N rests in close proximity to the tumbler K. This rod N is free to move longitudinally, and as the tumbler K is turned it strikes the end 55 of the rod N and moves it rearwardly and uncovers the mark or sign which indicates whether the triggers are locked or not. As the rod N is moved the cams v, passing through the restricted hole in the vertically-movable 60 bar w, elevate or depress the said bar, the movement of the said rod, however, being dependent on the direction of movement of the rod N. When the top lever, L, is turned to withdraw the bolts, the rod N is moved rearward and the bar w depressed, so as to bear directly on the triggers g and prevent them from 65 performing their functions. When the rod N reaches the end of its back stroke, the end of the spring O falls into a notch formed in the rod N and holds the said rod against accidental movement in either direction.
- When the parts are all adjusted, and it is desired to discharge a cartridge, it is simply necessary to move the thumb-piece P forward as far as it will go. This forward movement 70 of the rod N elevates the vertically-movable bar w, and leaves the triggers free to be moved. If it is desired to lock the gun after one barrel has been discharged, it is simply necessary to move the thumb-piece backward, which, as 75 before stated, depresses the bar w and locks the triggers.
- The gun-barrels are pivotally secured to the front end of the active body of the gun, between it and the movable portion Q of the 80 stock A. The front face or edge of the hooked catch or lug p is curved, as shown at y, against which curved portion the arms j of the cocking-bars H rest and on which they move. The half-circular notch a', situated immediately below the curved portion y, bears against the portion of the active body which forms the axis on which the barrels C move, and consequently when the barrel is tilted the curved portion y is moved in the arc of a circle away 85 from the active body and draws along with it the cocking-bars H. As soon as the required distance is traversed, the sears engage the hammers and hold them back in a cocked position. When the barrels are righted, the cocking-bars are also moved inward in position to engage the hammers for the next cocking.
- The fore part, Q, of the stock A is secured to the gun-barrels by the spring-actuated catch c', which, in outward appearance, resembles an 90 ordinary catch. The gun-barrels are also provided with a depending lug, b', having a notch on its rear face with which the spring-actuated catch engages. The lug b' projects downward into a close-fitting socket formed in the 95 portion Q of the stock, and the hooked catch c' engages with the notch therein and holds it firmly in place without danger of liability of displacement. The catch c' is operated by the lever d' and spring d', the latter tending to 100 hold the lever d' in a closed position. This construction of parts enables the fore part of the stock to be secured in position by simply placing the rear end thereof against the fore end of the active body and pressing the parts 105 together. During the operation the lever d' need not be touched and remains stationary, it being called into use only when desired to 110 take the gun apart.
- When it is desired to remove the barrels 115 from the stock, it is simply necessary to remove the fore part, Q, of the stock from the barrels. The top lever, L, is then turned, which releases the barrels from the active body and allows them to be removed for any purpose 120 whatever.
- When it is desired to load the gun, the top lever, L, is turned, which allows the barrels 125 to tilt, exposing the breech. This movement

of the barrels cocks the hammers and throws up the indicators, and the movement of the top lever locks the triggers and prevents any accidental explosion of a cartridge. The cartridges are then inserted in position and the breech closed by righting the barrels. When the gun is in this condition, it is impossible for an accidental explosion to take place, and before it can be fired the thumb-piece P has to be moved, so as to cover the safety-mark.

This gun in outward appearance resembles very closely the guns now commonly used by sportsmen; but in internal structure it differs materially. In the first place the front end of the stock, to which the active body is secured, is nearly solid, while those in guns now used are necessarily cut up to accommodate the complicated mechanism employed thereon. By means of our cocking-bars and the manner of connecting them to the barrels an immense leverage is obtained, and a corresponding striking force given to the hammer.

Our invention is simple in construction, is of comparatively few parts, can be entirely taken apart and put together with the aid of an ordinary screw-driver, and all the operative parts are of comparatively light and compact build and singularly frictionless in their workings.

It is evident that numerous changes in the position and construction of the several parts of the gun might be resorted to without departing from the spirit and scope of our invention, and hence we would have it understood that we do not limit ourselves to the exact construction shown and described, but consider ourselves at liberty to make such changes and alterations as fairly fall within the spirit and scope of our invention.

Having fully described our invention, what we claim as new, and desire to secure by Letters Patent, is—

1. In a breech-loading gun, the combination, with the hammers, each provided with a projection below its pivotal bearing, and tilting gun-barrels provided with a depending lug, of two sliding cocking-bars, each provided at its forward end with an inwardly-projecting lug, and adapted to engage the lug on the barrels at a point above the pivotal bearing of the barrels, and constructed to engage the projections on the hammers, substantially as set forth.

2. In a breech-loading gun, the combination, with the hammer provided with a projection below its pivotal bearing, and tilting gun-barrels provided with a depending lug having a curved bearing located above the pivotal bearing of the barrels, of a sliding cocking-bar provided at its forward end with a lug that engages the convex bearing on the lug of the barrels, and at its rear end with a lug that engages the projection on the hammer, substantially as set forth.

3. In a breech-loading gun, the combination, with an indicator-pin arranged to pass through

the breech-block, of the hammer constructed and arranged to directly engage the indicator-pin and impart a positive up-and-down movement thereto, substantially as set forth.

4. In a breech-loading gun, the combination, with an indicator-pin arranged to pass through the breech-block, said pin being provided with a slot or recess near its lower end, of a hammer provided with a finger or projection that engages in the slot or recess in the indicator-pin, and thereby imparts a positive up-and-down movement to the indicator-pin, substantially as set forth.

5. The combination, with the hammer, sear, and mainspring, of a pivoted dog adapted to engage the spring and lock it while the hammer is cocked, a lever constructed and arranged to engage the pivoted dog and release it from the spring, and trigger for operating said lever and the sear, substantially as set forth.

6. The combination, with the hammer, sear, trigger, and spring, the latter provided with a lateral projection, of a pivoted dog adapted to engage the lateral projection on the spring, one arm of said pivoted dog being notched, and a spring-actuated lever adapted to engage the notched end of the pivoted dog, said lever being operated by the trigger in releasing the spring, substantially as set forth.

7. The combination, with the gun-barrel, locking-bolt, top lever, and tumbler, of a compensating-link constructed substantially as described, and adapted to connect the locking-bolt and tumbler, substantially as set forth.

8. The combination, with the gun-barrel, locking-bolts, the tumbler, and top lever, of a compensating-link connecting the tumbler and locking-bolt, said link being made in two parts adjustably connected by a screw, substantially as set forth.

9. In a breech-loading gun, the combination, with the triggers and a locking-bar adapted to lock said triggers, of the top lever, tumbler, and devices, substantially as described, adapted to be operated by the tumbler and raise and lower said locking-bar, substantially as set forth.

10. In a breech-loading gun, the combination, with the locking-bolts, tumbler, top lever, and triggers, of a vertically-movable locking-bar adapted to engage with both triggers, and a reciprocating rod provided with a double cam for elevating and depressing said locking-bar, substantially as set forth.

11. In a breech-loading gun, the combination, with the locking-bolts, tumbler, top lever, and triggers, of a locking-bar adapted to engage with both triggers, a rod adapted to be retracted by a tumbler, said rod being provided with a double cam or incline for elevating and depressing said locking-bar, and a spring catch or pawl for locking said bar in a locked or unlocked position, substantially as set forth.

12. In a breech-loading gun, the combination, with the triggers and a locking-bar adapt-

ed to engage with both triggers, of a reciprocating rod provided with a double cam or incline for elevating and depressing said locking bar, and a thumb-piece attached to said reciprocating bar for actuating the same, substantially as set forth.

5 In testimony whereof we have signed this

specification in the presence of two subscribing witnesses.
